STOKER

William Thompson Hanna, Cincinnati, Ohio

Application November 6, 1928, Serial No. 317,621
Renewed January 24, 1935

12 Claims. (CL. 110—101)

This invention relates to stokers in general but more particularly to stokers for use on locomotives and the like.

One of the objects of this invention is to provide a stoker by which a preponderance of fuel may be directed to the center of the fire-box or toward the right hand or left hand sides thereof as desired.

Another object of the invention is to provide fuel conveying means which comprises a plurality of conveyors individually connected to driving means externally of the conduits in which the conveyors operate.

Another object of the invention is to provide a conveyor to feed fuel to the crushing device, said conveyor being power driven through a connection at its delivery end, thereby obtaining greater efficiency in the power applied to drive the conveyor due to the fact that its action is thus that of pulling instead of pushing as is ordinarily the case wherein a conveyor is driven at its receiving end.

These and other advantages are attained by the means described in the following specifications and disclosed in the accompanying drawings wherein:

Fig. 1 shows a sectional view of a stoker mechanism embodying this invention and taken substantially on a longitudinal center line.

Fig. 2 is a plan view of the mechanism shown in Fig. 1.

Fig. 3 is a front elevation in section of a portion of the mechanism which controls the direction of movement of fuel as it passes through the firing opening and is taken substantially on a line 3—3, Fig. 1.

Fig. 4 is an enlarged sectional view of a portion of the specific mechanism referred to in the reference to Fig. 3.

Fig. 5 is an external view of the entire stoker mechanism as viewed from the side opposite to Fig. 1.

Fig. 6 is a detail perspective view of one of the members shown in Fig. 3 which serves to control the direction of movement of the fuel as it passes through the firing opening.

In the drawings the back-head of a locomotive fire-box is represented by the numeral 10, the fire-box having the usual grate bars 11 and 50 firing opening 12. Embracing said opening and rigidly mounted on the outer face of the back-head is a fuel supply housing 13, which is provided with a delivery opening 13—b coinciding substantially with the firing opening 12. Substantially in alignment with the opening 13—b in

the opposite wall of said housing, is an opening 13—c which is embraced by a conventional form of fire-door plate 14, having an opening 14—a which serves as a fire-door opening, and upon which plate may be mounted the usual automatic fire-door (not shown), such as for example the Franklin butterfly type.

The housing 13 is arranged so that the lower side of the opening 13—b can be established in the form of a straight horizontal line or in the form of a V, with each side of the V arranged so as to be adjustable individually to various inclinations. This result may be accomplished in various ways, but in this instance I have shown adjustable members 15 and 16 each partially conical in form having facets 15—a and 15—b and 16—a and 16—b respectively. The members 15 and 16 are substantially alike in form and arranged relative to the firing opening as shown in Fig. 2. Each of said members is pivotally mounted in the side walls of the housing 13 and may be set in various angular positions by means of operating handles 17 and 18 rigidly secured to shafts 19 and 20 attached to the respective members. Each of the handles 17 and 18 is provided with an indexing sector 21 which is engaged by a spring-pressed retaining pawl 22, pivotally mounted on the housing 13, to hold the members 15 and 16 securely in any one of a plurality of angular positions, but the retaining device here shown is merely one of the expediencies, as it is obvious that the angular position of the members 15 and 16 may be fixed in adjusted position and by any suitable mechanism.

When the members 15 and 16 are set in the position shown in solid lines in Fig. 3, the facets 15—a and 16—a are in a horizontal plane, thus constituting in effect a horizontal shelf or ledge over which the fuel flows as it approaches the firing opening and thus the fuel is evenly distributed throughout the width of the fire-box. If, however, the members 15 and 16 are adjusted angularly so that each occupies the position shown in dotted lines in Fig. 3, a V is formed which has the effect of directing a preponderance of fuel toward the center of the fire-box. On the other hand, if only the member 15 should be adjusted to the position shown in dotted lines, a preponderance of fuel would be directed toward the left hand side of the fire-box and vice versa if only the member 16 were so adjusted. Thus variations in the angular positions of members 15 and 16 will produce variable results in the distribution of the fuel over the fire-bed.

Between the members 15 and 16, a section 13—d

of the wall of the housing 13 is so arranged that it is substantially in alignment with the facets 15—b and 16—b when the members 15 and 16 are in the position shown, thus forming, with these facets, a trough or chute over which the fuel moves preliminarily to its passage over the facets 15—a and 16—a.

The lower portion of the housing 13 is arranged in the form of a cylindrical conduit 13—e which surrounds the delivery end of a conveyor 23, the main portion of which is rotatively supported in a conduit 24 forming part of a sub-housing 24—a rigidly secured to the housing 13 and having an opening substantially flush with the deck 25 of the locomotive, through which fuel may be hand-fed directly to the conveyor 23 if desired. Positioned within the sub-housing 24—a is the delivery end of a conveyor 26 which is rotatively supported in a housing or conduit 27, the forward end of which has a universal connection with the sub-housing 24—a below the deck of the locomotive. The opposite end of the conduit 27 is slidably surrounded by a member 28 which is arranged to have a universal connection with a housing or conduit 29 rigidly secured to the front face of the tender hopper 30.

The design and construction of the housing or conduit 29 is of such a character that the cross-sectional area of the chamber within said conduit increases from the entrance at the tender hopper end to the portion which surrounds the member 28. Thus the fuel passing through the conduit 29 is offered greater freedom as it approaches the conveyor 26 with the result that the tendency of the fuel to pack is minimized.

The tender hopper 30 is preferably in the form of a trough and is mounted in any suitable manner upon the tender 31, and in this instance is preferably arranged to incline toward the delivery end. Above the tender hopper 30 is the usual tender deck 31—a arranged so as to permit various areas thereof to discharge fuel into said hopper. Rotatively supported within the trough of the tender hopper 30 is a conveyor 32 which has its delivery end partially surrounded by a crushing member 33 which may be of any suitable character, but in this instance is shown as being rigidly secured to the inside front face of the tender hopper. The hub portion of the conveyor 32 is extended beyond the delivery end thereof and has a universal connection with the shaft 34 journaled in the wall of the conduit 29, and the opposite end of the conveyor is preferably confined in the trough by means of a retaining plate 35 rigidly secured to the trough 30.

The operating mechanism for the conveyors 23, 26 and 32 may be of any suitable character, but in this instance I have shown it as comprising a power-device in the form of a steam motor 36 like that disclosed in my U. S. Patent No. 1,577,462 in which the primary transmission element comprises a rack and pinion and it is this form of primary transmission element that I prefer to have embodied in the power device for operating a stoker of the character described herein, but it will be understood that other forms of transmission element may also be used effectively.

The power-device 36 is operatively connected with the conveyor mechanism by means of a suitable shaft 37 universally connected at one end to the power-device and similarly connected at its opposite end with a shaft 38 suitably supported for rotation on the tender hopper. A gear 39 is rigidly secured to the shaft 38 and meshes with a gear 40 rigidly secured to a shaft 41 suitably

journaled on the conduit 29. The gear 39 also meshes with a gear 42 rigidly secured to the shaft 34. The shaft 41 is operatively connected with the conveyor 23 by means of a suitable shaft 43. Also, rigidly secured to the shaft 38 is a gear 44 which meshes with a gear 45 rigidly secured to a shaft 46 suitably journaled on the tender hopper 30. The shaft 46 is operatively connected to the conveyor 26 by means of the shaft 47.

The arrangement and construction of parts of the hopper and transfer mechanism is covered in my co-pending application, Serial No. 94,499, filed August 6, 1936.

The power-device, of whatever character, preferably should be provided with a control lever such as the lever 48 for starting and stopping rotation of the conveyors.

Such a stoker is preferably provided with means to more efficiently distribute the coal after it has passed through the firing opening 12 and for this purpose, I prefer a blast chamber of suitable type as 49 and a distributor plate 50 positioned at the entrance of the firebox immediately below the delivery opening 13—b of the housing 13.

It will be understood that the invention may be variously modified and embodied within the scope of the subjoined claims.

I claim:

1. In a stoker mechanism for a locomotive and tender, in combination, fuel transfer mechanism located below the deck of a locomotive tender, a conveyor arranged to receive the fuel from said transfer mechanism and convey it to said locomotive, a housing having an aperture through which fuel may be received from the delivery end of said conveyor, means within said housing arranged to receive the fuel passing through said aperture and adapted to force said fuel through the firing opening of the locomotive, said housing including a bottom wall having a plurality of tilttable sections adapted to form an adjustable ledge within said housing adjacent said firing opening whereby fuel passing thereover may be directed to the center of said firing opening or deflected to one side or the other thereof, and a distributor plate to receive the fuel from said housing.

2. In a stoker mechanism, in combination, a fire box having a firing opening, a fuel supply housing embracing said opening, a fuel tender, fuel crushing means mounted on said tender and including a conveyor, a power device operatively connected to said conveyor at its delivery end, transfer mechanism for transporting fuel from said conveyor to said housing, tilttable sections mounted in the floor of said housing adjacent said firing opening whereby the fuel passing thereover may be directed to the center of said firing opening or deflected to one side or the other thereof, and a distributor plate in said firing opening to receive the fuel from said housing.

3. In a stoker mechanism, in combination, a fire box having a firing opening, a fuel supply housing, conveying means for moving fuel from a source of supply to and through said housing, and adjustable means including rockable members arranged within said housing adjacent said firing opening, said rockable members forming at least a portion of the fuel supporting surface of said housing, whereby fuel passing through said housing passes over said rockable members and may be directed toward the center of said opening or deflected to one side or the other.

thereof by adjusting the positions of said rockable members.

4. In combination with a fire box having a firing opening, a stoker mechanism comprising a fuel supply housing having a delivery opening communicating with said firing opening and including a bottom wall for supporting fuel supplied thereto; a conduit communicating with said housing for feeding fuel to and through said housing; fuel-directing means in said housing including movable members mounted in said bottom wall and forming a part of the fuel supporting surface thereof; and means for adjusting said members to change the angle of the fuel supporting surfaces thereof with respect to the bottom wall, whereby the flow of fuel through said housing may be directed.

5. In combination with a fire box having a firing opening, a stoker mechanism, comprising a fuel supply housing having a delivery opening communicating with said firing opening and including a bottom wall for supporting fuel supplied thereto; a conduit communicating with said housing for feeding fuel to and through said housing; fuel-directing means in said housing including movable members mounted in said bottom wall and forming part of the fuel supporting surface thereof; and means for adjusting said members to change the angle of the fuel supporting surfaces thereof with respect to the bottom wall, whereby the flow of fuel through said housing may be directed.

6. In combination with a fire box having a firing opening, a stoker mechanism, comprising a fuel supply housing having a delivery opening communicating with said firing opening and including a bottom wall for supporting fuel supplied thereto; means communicating with said housing for feeding fuel to and through said housing; fuel-directing means in said housing including movable members mounted in said housing and forming a part of the fuel supporting surface of said bottom wall; and means for adjusting said members to change the angle of the fuel supporting surfaces thereof with respect to the bottom wall, whereby the flow of fuel through said housing may be directed.

7. In combination with a fire box having a firing opening, a stoker mechanism, comprising a fuel supply housing having a delivery opening communicating with said firing opening and including a bottom wall for supporting fuel supplied thereto; the lower edge of said delivery opening constituting in effect a ledge over which the fuel flows in moving from said housing into said firing opening; a conduit communicating with said housing for feeding fuel to and through said housing; fuel-directing means in said housing including movable members mounted in said housing and forming a part of the fuel supporting surface thereof, and means for adjusting said members to change the effective height of said ledge whereby the flow of fuel through said housing may be directed.

8. In combination with a fire box having a firing opening, a stoker mechanism, comprising a fuel supply housing having a delivery opening communicating with said firing opening and including a bottom wall for supporting fuel supplied thereto; a conduit communicating with said housing for feeding fuel to and through said housing; fuel-directing means in said housing including movable members mounted in said bottom wall, and resembling a frustum of a pyramid,

some of the faces of said members forming a part of the fuel supporting surface of said bottom wall; and means for adjusting said members to change the angle of said faces with respect to the bottom wall, whereby the flow of fuel through said housing may be directed.

9. In combination with a locomotive and tender, a stoker mechanism comprising a fuel supply housing having a delivery opening communicating with the fire box of said locomotive, and including a bottom wall for supporting fuel supplied thereto; a conduit communicating with said housing for supplying fuel thereto, said conduit having a receiving opening at its receiving end; a conveyor for moving fuel from said tender to said locomotive, and communicating with the receiving opening of said conduit; and a passage communicating with the floor of said locomotive and said receiving opening whereby fuel may be supplied to said conduit manually and/or by said conveyor; fuel-directing means in said housing including movable members mounted in said housing and forming a part of the fuel supporting surface of said bottom wall; and means for adjusting said members to change the angle of the fuel supporting surfaces thereof with respect to the bottom wall, whereby the flow of fuel through said housing may be directed.

10. In combination with a fire box having a firing opening, a stoker mechanism, comprising a fuel supply housing having a delivery opening communicating with said firing opening and including a bottom wall for supporting fuel supplied thereto; a conduit communicating with said housing for supplying fuel thereto; fuel-directing means in said housing including movable members mounted in said bottom wall and forming part of the fuel supporting surface thereof; and manually operable means for adjusting said members to change the angle of the fuel supporting surfaces thereof with respect to the bottom wall, whereby the flow of fuel through said housing may be directed; and means for retaining said manually operable means in any adjusted position.

11. In a stoker mechanism, in combination, a fire box having a firing opening, a source of fuel, a conduit for conveying said fuel to said firing opening, said conduit expanding as it joins said firing opening, adjustable fuel guiding means pivotally mounted in the expanded portion of said conduit and the upper portions thereof serving as fuel supporting surfaces, and manually operable means for pivoting said fuel guiding means about their longitudinal axes to rotate said means to change the angular relationship of said upper portions with respect to the floor of said conduit.

12. In a stoker mechanism, the combination with a fire box having a firing opening, of a conduit for conveying fuel from a source of supply to the firing opening, means for moving fuel therethrough to the firing opening, and means for distributing fuel fed through said opening over the fire; and fuel directing means interposed between said fuel moving means and said fuel distributing means and located beneath the path of the fuel, said means being adjustable on an axis oblique to the path of the fuel by tilting and having an angular protruding fuel supporting surface, the angle of which with respect to the horizontal is changeable by tilting the said means to change the direction of the flow of fuel to said distributing means.

WILLIAM THOMPSON HANNA.
